LEATHER WORKING MACHINE

John Edgar Leach, Bristol, Pa., assignor to Fulton County Machine and Supply Co., Inc., Gloversville, N. Y., a corporation of New York

Application July 30, 1940, Serial No. 348,590

2 Claims. (Cl. 149—16)

This invention relates to leather shaving and like machines, and a principal object of the invention is to provide an efficient and generally improved machine of this class.

A specific object of the invention is to provide, in a machine of this character, novel and improved means for maintaining the blades of the work cylinder in sharp condition, said sharpening means constituting an operative part of the machine and obviating hand-sharpening operations and interruption of the machine during the sharpening process.

Another object is to provide novel and improved means for guiding the work to the work cylinder and for maintaining a constant relation between the elements of the guiding and feeding mechanism.

Still another object of the invention is to provide novel and improved means for adjusting the machine for different thicknesses of skin or leather and to regulate the depth of cut.

The invention resides further in certain structural and mechanical details hereinafter set forth and illustrated in the attached drawings, wherein:

Figure 1 is a side elevational view of a machine made in accordance with my invention;

Fig. 2 is a front elevational view of the machine;

Fig. 3 is a fragmentary plan view embracing that portion of the machine indicated by the line 3—3, Fig. 4;

Fig. 4 is a section on the line 4—4, Fig. 2;

Fig. 5 is an enlarged fragmentary sectional view taken on the same line as Fig. 4 and illustrating certain details of mechanism;

Fig. 6 is a section on the line 6—6, Fig. 5;

Fig. 7 is a fragmentary view in perspective of one of the elements shown in Figs. 5 and 6;

Fig. 8 is an enlarged partial sectional view illustrating a detail of mechanism;

Fig. 9 is a section on the line 9—9, Fig. 1;

Fig. 10 is an enlarged fragmentary front elevational view of one of the details of mechanism shown particularly in Fig. 2;

Fig. 11 is a fragmentary sectional perspective view illustrating a modification within the scope of the invention;

Fig. 12 is a sectional view on the line 12—12, Fig. 11;

Fig. 13 is a sectional plan view of that portion of the machine shown in Fig. 12;

Fig. 14 is a fragmentary perspective view on the line 14—14, Fig. 12, and

Fig. 15 is a detached sectional perspective view

of one of the elements of the mechanism shown in the immediately preceding figures.

With reference to the drawings, the machine comprises a suitable frame 1, at the rear end of which is mounted an electric motor 2. This motor is connected through belts 3 and pulleys 4 and 5 with a shaft 6 which is journaled in suitable bearings 7 also at the rear of the frame. At each end of the shaft 6 is a pulley 8, and these pulleys are connected through belts 9, 9 with pulleys 11, 11 at opposite ends respectively of a shaft 12, this shaft being journaled in suitable bearings 13, 13 at the top forward end of the frame. The shaft 12 carries a work cylinder 14 which in the present instance is provided with a series of spirally arranged cutting blades 15, see Figures 3 and 4, and these blades constitute the active leather-shaving elements.

Mounted at the top and in the mid section of the frame 1 is a transverse guide 16, and slidably mounted on this guide is a carriage 17. Journaled in the opposite ends of the guide 16 is a screw shaft 18, and this shaft passes freely through a pair of spaced flanges 19 which depend from the bottom of the carriage 17 through a longitudinal opening 21 in the member 16. Confined closely between these flanges is a nut 22 which meshes with the threads of the shaft 18, the nut being restrained against rotation so that when the said shaft is rotated, the nut and with it the carriage 17 will be advanced transversely of the machine upon the guide 16 and in one or other direction, depending upon the direction of rotation of the screw shaft 18.

As shown in Fig. 1, the shaft 18 carries at one end a gear 23, and this gear meshes with a pinion 24 which is mounted on a stub shaft 25, this latter shaft being journaled at one end in a bearing formed between the top of the frame 1 and the base of the guide member 16, and at the other end in a bracket 26 secured to the inside of the casing, as shown in Figs. 3 and 4. The stub shaft 25 carries three pulleys 27, 28 and 29, of which the pulley 28 is secured to the shaft, while the pulleys 27 and 29 are idlers and are free to rotate upon and with respect to the shaft. A corresponding set of three pulleys 31 are secured to the shaft 6 in alignment with the pulleys 27, 28 and 29, see Fig. 4, and between the two groups of pulleys extend two belts 32 and 33, the belt 33 being crossed as illustrated. In Fig. 3, it will be noted that the flat belt 32 is engaged with the idler pulley 27, while the twisted belt 33 engages the intermediate active pulley 28. These two belts are adapted to be shifted, by means herein-

after described, to positions in which the flat belt 32 engages the active pulley 28, while the twisted belt 33 engages the other idler pulley 29. The direction of rotation of the shaft 25, therefore, will depend upon which one of the belts 32 and 33 is at the moment in engagement with the active pulley 28.

The belt-shifting device is illustrated in Figs. 1, 3, 4 and 9. It consists of a rod 34 which extends in parallel relation to the guide 16 and shaft 18 and which is slidably supported in the opposite sides of the frame 1. This rod has attached thereto forks 35 and 36 which respectively embrace the belts 32 and 33. The proximate end 37 of the rod 34 is flattened to rectangular shape and projects through a correspondingly shaped opening in the frame 1, and this flattened extremity is provided towards its outer end and on the under side thereof with two notched recesses 38 and 39. Pivotedly secured at 41 to the wall of the frame 1 is a lever 42, one end of this lever carrying a weight 43 and the other a knife edge 44 which is adapted to engage the notches 38 and 39, as best illustrated in Fig. 9. When the end 44 of the lever 42 engages the notch 38, the rod is in the longitudinal position of adjustment shown in Fig. 3. When the rod is shifted longitudinally to an extent bringing the lever end 44 into the notch 39, the forks 35 and 36 will have been moved to an extent such that the belt 33 is shifted to the idler pulley 29 and the belt 32 to the active pulley 28. This shifting of the belts will obviously result in a reversal of the direction of rotation of the shaft 25, and since this shaft is operatively connected through the pinion 24 and gear 23 with the screw shaft 18, shifting of the belts as described will also result in a reversal of direction of the latter shaft.

The carriage 17 carries a depending arm 45, the lower forked end of which embraces a flanged collar 46 slidably supported on the rod 34, the said arm being confined between the terminal flanges 47, 47 of the collar. Supported on opposite ends of the rods are coiled springs 48 and 49, the outer end of the spring 49 bearing against the end of the belt shifter 35-36, and the outer end of the spring 48 against a collar 51 secured to the proximate end of the rod 34. When the carriage 17 has advanced in the one direction to an extent bringing the collar 46, through the arm 45, into operative engagement with the spring 49, the spring will be compressed and will eventually exert sufficient pressure against the belt shifter 35-36 to shift the belts 32 and 33 as previously described so that the belt 32 will engage the pulley 28 and the belt 33 the idler pulley 29. This will effect a reversal of the screw shaft 18 as previously set forth and will actuate the carriage 17 toward the opposite side of the machine until the forked arm 45 is eventually brought into operative engagement with the spring 48. Increasing pressure on this spring will eventually cause a shifting of the rod 34 and of the belt shifter 35-36 to return the belts 32 and 33 to the position shown in Fig. 3, thus again effecting a reversal of the screw shaft 18 and of the carriage 17. The weighted lever 42 in coaction with the notches 38 and 39 restrains the rod 34 against movement until the springs 49 have been compressed to a certain extent, and the energy thus stored in the springs effects a desirable quick action of the belt shifter. The aforescribed transverse shuttle movement of the carriage 17 is continuous during the operation of the machine.

The carriage 17 has an upper relatively movable section 52 which is adjustable on the inclined face 53 of the carriage through the medium of a hand wheel 54. This upper section 52 carries an electric motor 55 which is connected through a belt 56 and pulleys 57 and 58 with a shaft 59 journaled in the lower portion of the adjustable carriage section 52. This shaft carries an abrasive wheel 61, the peripheral face of which is adapted to contact the outer edges of the blades 15 of the rotary shaving cylinder 14, as best shown in Figs. 3 and 4. As the carriage 17 is traversed on the guide 16 as described above, the rotating abrasive wheel 61 will be carried longitudinally across the face of the shaving drum, and will thereby maintain the outer active edges of the blades 15 in sharp condition. Adjustment of the abrasive wheel 61 into proper contact with the blades of the drum 14 is effected by adjustment of the upper section 52 of the carriage 17 through the medium of the hand wheel 54 as previously described.

As shown in Figs. 1, 3 and 4, the cross carriage 52 is held to the carriage 17 by dovetail guides 62, 62. The hand wheel 54 is attached to a shaft 63 journaled in the wall of the carriage 52, and this shaft carries a bevel pinion 64 which meshes with a bevel gear 65 on a screw shaft 66 also journaled, at 67, on the carriage 52. The screw shaft 66 engages a nut 68 which is fixed to the carriage 17, so that when the shaft is turned, the carriage 52 is adjusted on the guides 62 for the purpose set forth.

Mounted at the front end and at each opposite side of the frame is a bracket 71. Secured in each of these brackets is a guide rod 72, and supported for sliding movement on the rod is a member 73. Each of the members 73 has a forwardly projecting arm 74, and mounted on these arms and extending transversely of the machine is a table 75. As shown in Fig. 3, the upper surface of this table is provided with a series of grooves 76, the function of which will be herein-after described. Supported in each of the brackets 71 for longitudinal sliding movement is an adjusting rod 77, the inner end portion of this rod having threaded engagement with the associated member 73. The inner extremity of the rod 77 is adapted to bear against the back of the bracket 71, and the rod thereby constitutes an adjustable stop to limit the movement of the member 73 in one direction.

Operatively connected to each of the members 73 is a bell crank lever 78, see Figs. 2 and 4, and this lever is connected, through an adjustable rod 79, with a lever 81 which is fixed to a rock shaft 82 journaled in and extending between the side plates of the frame 1. The rear end of each of the levers 81 is weighted, as indicated at 83, and the forward ends of the said levers 81 jointly support a treadle 84. Normally the weights 83 hold the rear ends of the levers 81, to which the connecting rod 79 is attached, in a depressed position whereby, through the bell crank levers 78, the members 73 are held in an advanced position, wherein the inner ends of the adjusting rods 77 bear against the inner ends of the brackets 71, as previously described. Under these circumstances, it will be apparent that by rotating the rods 77, the positions of the members 73 in the respective brackets 71 may be regulated, or rather the extent to which the members 73 may move towards the rear ends of the brackets. When the rear ends 75 of the levers 81 are elevated by pressure on the

treadle 84, the members 73, together with the table 75 which is supported thereby, will be traversed in the brackets 71 towards the front of the machine.

Journaled in the members 73 is a feed roll 85, preferably rubber covered, and this roll is adapted to cooperate with the work cylinder 14, as best shown in Fig. 4. The extent to which the roll 85 is permitted to approach the work cylinder 14 is controlled by the adjustment of the rods 77 in the manner previously described. Preferably there is sufficient play between the members 73 and the guide rods 72 to permit slight independent adjustment of the opposite ends of the roll so as to bring the surface of the roll into accurate alignment with the periphery of the work cylinder 14.

The outer ends of the adjusting rods 77 are provided with dials 86 which cooperate respectively with pointers 87 supported on the arms 74 of the members 73. As shown in Fig. 8, the dials 86 are adjustable upon the rods 77 angularly, and are held securely in adjusted position by means of a lock nut 88. These dials provide for accurate adjustment of the feed roll 85 with respect to the work cylinder 15 and also the opposite ends of the feed roll so as to bring the latter into accurate alignment with the work roll. The feed roll 85 is rotated through the medium of a belt 89, see Fig. 1, which operatively connects a pulley 91 on the shaft 92 of the feed roll with a pulley 93 carried by a stub shaft 94 which is journaled in a bracket 95 secured to one of the side plates of the frame 1. The stub shaft 94 carries on its inner end a gear 96 which meshes with a pinion 97 on a shaft 98 journaled in the frame and carrying at its outer end a pulley 99, this pulley being connected through a belt 101 with a pulley 102 on the shaft 6. It is apparent that the belt 89 provides for the traversing movements of the feed roll 85 previously described.

Immediately above the feed roll 85 is a pinch roll 103, this roll being adapted to engage the peripheral surface of the feed roll. The pinch roll 103 is supported at its opposite ends in journals 104, and as shown in Figs. 5 and 6, each of these journals is slidably supported in a journal-box 105 secured to the fixed frame 1 through the medium of screws 106. Each of the journals 104 is adjustably supported in the box through the medium of a threaded rod 107 which extends upwardly through a hollow adjusting screw 108 threaded into the top of the box 105. The inner end of the rod 107 is pivotally secured to the journal 104 through the medium of a retaining screw 109, and the upper end of the rod is provided with adjusting and lock nuts 111 and 112, the adjusting nut 111 engaging the top of the hollow screw 108. This latter screw is fixed in adjusted position in the box 105 through the medium of a lock nut 113. A spring 114 is confined between the top of the journal 104 and the inner or lower end of the adjusting screw 108 and exerts a resilient pressure tending to hold the journal in a depressed position with respect to the adjusting screw 108. The normal position of the journal in the box, therefore, may be determined by adjusting the position of the screw 108 in the journal box, and the tension of the spring 114 may be regulated by adjusting the rod 107 in the adjusting screw 108.

As shown in Figs. 5 and 6, the pinch roll 103 is provided with a series of circumferential

recesses 115, and these recesses provide for passage between the pinch roll and the feed roll 85, and past the bite of these rolls, of a corresponding series of fingers 116, which as shown in Fig. 5 follow the curve of the feed roll 85 and extend into proximity to the blades 15 of the work cylinder 14. The fingers 116 are supported by and depend from a bar 117 which is secured to the inside of an angle bar 118, the ends of this bar being rigidly secured respectively to the journals 104. The function of the fingers 116 will be hereinafter described. It will be noted that the angle bar 118 also functions to support the forward end of a guard plate 119 which extends upwardly and rearwardly over the work cylinder 14 and the grinding wheel 61.

Mounted on the rear inner end of the table 75 through the medium of brackets 121 is a guard plate 12, this plate extending across the full width of the machine between the side members of the frame 1, and preventing access to the feed roll 85 and pinch roll 83 except through a narrow slot 123 at the lower edge of the plate 122 and between the lower edge and the upper surface of the table 75. This slot is preferably only of sufficient width to permit ready passage of a skin to the machine, but prevents the fingers of the operator from contacting either of the rolls.

Below the work cylinder 15 and in peripheral contact with the latter is a rotary brush 124, this brush being supported at opposite ends in journals 125 supported respectively on bars 126, the rear ends of which bars are pivotally secured on a rod 127 extending transversely across the frame 1. The forward ends of the bars 126 are supported on brackets 128 secured to the frame 1 through the medium of adjusting screws 129 whereby the forward ends of the bars may be adjusted vertically to in turn adjust the position of the roll 124 with respect to the work cylinder. The cylindrical brush 124 is rotated in the direction of the arrow shown in Fig. 4 by means of a belt 131 which operatively connects a pulley 132 on the brush shaft with a pulley 133 on the shaft 98. The bars 126 also constitute a support for a series of rods 134 which extend upwardly and over the body of the rotary brush 124, as shown in Figs. 2 and 4, and between the bristles of the brush, these rods being secured in transverse bars 135-136 secured to and extending between the bars 126. The function of the brush 124 and of the rods 134 will be hereinafter described.

A second rotary brush 137 is journaled in brackets 138 depending from the under side of the table 75, and this brush peripherally engages the feed roll 85. The shaft of the rotary brush 137 carries a pulley 139 which is connected through a crossed belt 141 with a pulley 142 on the shaft 98 whereby the brush is rotated in the direction indicated by the arrow in Fig. 4. It will be noted further that the transverse bar 127 constitutes a support for a hopper 143, the open top of which immediately underlies the work cylinder 14 and the immediately associated rolls.

In the operation of the machine as described above, the operator, after depressing the treadle 84, slides the skin rearwardly on the table 75 under the guard plate 122 and into the space between the pinch roll 103 and the feed roll 85. In placing the skin upon the table, the grooves 76 in the surface of the latter preclude the trapping of air between the skin and the table top and give assurance that the skin will lie flatly upon

the table. After inserting the skin as described above, the treadle 84 is released, with the result that the weights 83 carry the feed roll rearwardly into engagement with the pinch roll and into close proximity to the blades 15 of the work cylinder 14. The adjustment of the rods 77 as previously described determines the spacing of the surface of the feed roll 85 from the edges of the blades 15 of the work roll, and thereby determines the depth of cut. The clamping of the skin in the bite of the feed roll 85 and the pinch roll 163 draws the skin inwardly towards the work cylinder, and the fingers 116 prevent any tendency of the skin to turn upwardly around the pinch roll, and insure that the skin shall be fed flatly and without folds to the work cylinder. As the skin passes downwardly between the feed roll and the work cylinder, the rotary brush 124 takes effect to throw the lower edge of the skin forwardly towards the front of the machine, and the rotary brush 137 precludes the skin from feeding upwardly with the feed roll, and guides it downwardly onto the rods 134, which in turn guide the skin outwardly at the front of the machine. During the operations described above, the grinding wheel 61 is being traversed between the opposite sides of the machine and in engagement with the outer or cutting edges of the blades 15. The various adjustments previously described give assurance of uniform operation on the skin by insuring proper and accurate alignment between the blades of the work cylinder and the opposed surface of the feed roll 85.

In Figs. 11 to 15, inclusive, I have shown a modification within the scope of the invention. In this case, the function of the fingers 116 is performed by a rigid angle bar 144 which extends transversely of the machine below a pinch roll 145 and in proximity to the surface of a feed roll 146. The respective opposite ends of the pinch roll 145 are journaled in this instance in a bearing 147 carried by a bracket arm 148 which is pivotally secured at 149 to a bracket 151 mounted on the frame. The free end of the arm 148 is supported by a set screw 152 which is adjustably secured in a lug 153 on the said arm 148 and bears upon a lug 154 on the fixed bracket 151. A rod 155 extends loosely through the lug 153 and downwardly through a bracket 156 on the frame 1, and a nut 157 on the said rod 155 engages the under side of the bracket 156 and acts as a stop preventing upward movement of the said rod. A spring seat 158 is held in position on the upper end of the rod 155 by means of a nut 159, and a spring 161 is confined between the seat 158 and a corresponding seat 162 which bears against the top of the lug 153 of the arm 148. This spring 161 exerts pressure tending to hold the arm 148 in the depressed position, wherein the set screw 152 engages the lug 154.

The bar 144 is rigidly secured at each end to a collar 163, which as best shown in Fig. 13 embraces the bearing 147. The sleeve 163 has an arm 164 containing a segmental slot 165 concentric with the sleeve. In assembly and as shown

in Fig. 13, the arm 164 lies flatly against the face of the bracket arm 148, and is secured to the latter by means of a screw 166 which passes through the slot 165. When the screw 166 is loosened, the collar may be adjusted around the bearing 147, with the result that the bar 144 is adjusted with respect to the surface of the feed roll 146. It will be apparent that the bar 144 functions to guide a skin inserted between the feed roll 146 and the pinch roll 145 flatly to the work cylinder 167, and prevents the skin from curling up around the pinch roll 145. In all other respects, the mechanism shown in Figs. 11 to 15, inclusive, corresponds to that disclosed in the preceding figures.

While the invention is herein described and illustrated in its application to a leather shaving machine, it will be apparent that it is equally applicable to other machines of the same general character, such, for example, as buffing machines, and term "work cylinder" is, therefore, to be construed to cover other characters of work element than the bladed shaving cylinder herein illustrated.

I claim:

1. In a machine of the character described, the combination with a rotary work cylinder, of a pressure roll coactive with the work cylinder to maintain the work in operative engagement with said cylinder, a pinch roll coactive with the pressure roll to feed the work to the cylinder, pivoted arms providing journals for said pinch roll, and means for adjusting said arms to regulate the normal position of said pinch roll with respect to the pressure roll, and a guide member mounted on said arms for adjustment about the axis of said pinch roll, said guide member extending continuously from the surface of the pinch roll, and from a line on said surface in proximity to the nip of said roll with the pressure roll, toward the work cylinder, said guide means following the contour of and lying throughout in proximity to the surface of the pressure roll and terminating in proximity to the nip of the pressure roll with the work cylinder.

2. In a machine of the character described, the combination with a rotary work cylinder, of a pressure roll coactive with the work cylinder to maintain the work in operative engagement with said cylinder, a pinch roll coactive with the pressure roll to feed the work to the cylinder, an adjustable support for the pinch roll, said support comprising cylindrical journal elements for the roll, a guide member journaled on said elements and adjustably secured to said support, said guide comprising a rigid element extending continuously from the surface of the pinch roll, and from a line on said surface in proximity to the nip of said roll with the pressure roll, toward the work cylinder, said guide means following the contour of and lying throughout in proximity to the surface of the pressure roll and terminating in proximity to the nip of the pressure roll with the work cylinder.

JOHN EDGAR LEACH.
